UNITED STATES PATENT OFFICE

2,676,530

EXHAUST FAN

Samuel M. Bernstein, Chicago, Ill.

Application December 18, 1947, Serial No. 792,562

1 Claim. (Cl. 98—116)

1

The invention relates to exhaust fans and more particularly to fans provided with a shutter.

In installing exhaust fans with shutters according to standard practice a double installation is necessary by first securing the blower in proper position and subsequently attaching the shutter.

According to my invention it is an object to provide an exhaust fan to which the shutter is already secured so that a simplified and expeditious method of installing the unit is afforded.

It is a further object to provide the frame of the fan with means for readily attaching the shutter to the frame so as to provide an operable unit.

It is also an object to provide certain features of construction and arrangement of parts tending to enhance the utility and efficiency of a device of the character specified.

With these and other objects in view which will become apparent from a disclosure of the invention, the latter comprises the means described in the following specification, particularly pointed out in the claim forming a part thereof, and illustrated in the accompanying drawings, in which

Fig. 1 is the front view of an exhaust fan constructed in accordance with my invention.

Fig. 2 is a rear view thereof.

Fig. 3 is an enlarged section on the line 3—3 of Fig. 1.

Fig. 4 is an isometric view of the frame, only.

Fig. 5 is an enlarged section on the line 5—5 of Fig. 3.

Fig. 6 is a fragmentary isometric view of a corner of the frame.

Referring to the several views of the drawing 10 designates a wall in which an opening 11 is provided with a wooden frame 12.

A front plate 13 is secured to the wooden frame by screws 14 and is provided with a large circular opening 15, the edge of which is bent inwardly to form a circular flange 16.

To the front plate 13 is secured as at 17 a horizontal arm 18 which is bent upwardly to form a support 19 for a platform 20.

Bracket arms 21 and 22 leading from the platform to the front plate further maintain the platform in functional position.

A motor 23 having a base 24 is secured by bolts 25 to the platform.

The motor shaft 26 carries at its free end a fan 27.

The parts thus far described do not per se form a part of the invention.

To the outer side of the front plate (Fig. 4) is

2

secured a rectangular frame 28 made up of four angle irons 28A one leg 28B of each of which is welded to the front plate or secured in any other preferred or approved manner, so that the angles 5 lie end to end in a rectangular array, while the remaining sides or legs of the several angles all project outwardly to define a square flange to fit into the opening of the wall 10.

A Z-bar 29 is secured to the upper side 30 of 10 the frame and a vertical channel member 31 (Fig. 6) is secured to each side member 32 by screws 33.

Each channel member is provided with a plurality of vertically spaced openings 34, and the 15 pivot openings of both channel members are in horizontal registry.

Pivot rods 35 (Fig. 5) are journaled in appertaining pairs of openings 34 of the channel members and have rigidly secured thereto louvers or 20 shutter plates 36 in overlapping relation to form a shutter 37 which closes when the fan is not running to shut out back flow and weather.

A vertical link bar 38 is connected by diagonally 25 and rectangularly offset arms 39 to each louver 25 so that the opening and closing movements of said louvers are synchronized as will be readily understood by those versed in the art.

It is evident that the blower and shutter when 30 assembled may be handled as a unit and thus facilitate installation and removal from the wall opening.

The method employed in assembling the blower 35 and shutter eliminates labor in installing as compared with the present day practice of individually installing the blower and subsequently the shutter.

While the drawing shows one embodiment of 40 the invention, numerous changes and alterations may be made without departing from the spirit of the invention.

I, therefore, wish to include all modifications, rearrangements and revisions constituting departures within the scope of the invention, as defined in the appended claim.

45 I claim:

In an exhaust fan structure, a rectangular plate adapted to fit over a wall opening and having a round central aperture; a mounting bracket 50 for a motor fan secured on one side of said plate in alignment with said aperture; a rectangular flange defining a shallow frame on the opposite side of said plate from said mounting bracket and surrounding said aperture, said plate and frame flange defining a shallow compartment; and a set 55 of pivoted louvers mounted in said shallow com-

partment to extend fully across the same, each louver having pintle means at opposite ends thereof, a channel member on the inside of each one of a pair of opposite portions of said rectangular flange and respectively having said pintle means seated therein; together with an annular baffle flange on said plate and surrounding said aperture and projecting into said shallow compartment but having its innermost margin terminated short of said louvers so as not to obstruct the free pivotal movement of the louvers.
